Patented Apr. 27, 1915.

Fig. 1.

UNITED STATES PATENT OFFICE.

ALLISON F. GODDARD, OF RANKIN, ILLINOIS.

ROTARY FLY-BRUSH.

1,137,602.

Specification of Letters Patent. Patented Apr. 27, 1915.

Application filed May 9, 1914. Serial No. 837,469.

To all whom it may concern:

Be it known that I, ALLISON F. GODDARD, a citizen of the United States, residing at Rankin, in the county of Vermilion and State of Illinois, have invented new and useful Improvements in Rotary Fly-Brushes, of which the following is a specification.

The invention relates to rotary fly brushes, and more particularly to improvements on the construction of fly brush forming the subject matter of my pending application, filed on or about September 3, 1913, and serially numbered 787,967.

The primary object of the invention is the provision of a fly brush wherein the hub or spool of the brush is reinforced so as to prevent the possibility of the splitting thereof at either end of the same, thus increasing the life of the brush.

Another object of the invention is the provision of a brush wherein the arms thereof are mounted in a novel manner to reinforce the hub or spool and to render the same thoroughly serviceable.

A further object of the invention is the provision of a brush of this character which is extremely simple in construction, thoroughly reliable and efficient in operation, strong, serviceable, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawings:—Figure 1 is a fragmentary front elevation of a screen door, showing the brush constructed in accordance with the invention mounted thereon. Fig. 2 is an enlarged vertical sectional view through the same. Fig. 3 is a perspective view of the brush.

Similar reference characters indicate corresponding parts throughout the several views in the drawing.

Referring to the drawing by numerals, 1 represents a portion of an ordinary door frame to which is hinged a screen door 2. Secured to the door 2 rearwardly of the wire mesh 3 carried thereby is a vertical strip 4 in which is mounted a bolt 5 rotatably supporting the brush hereinafter fully described.

Rotatably supported upon the bolt 5 is

a brush which comprises a hub or spool 6 having an outer flared end forming a head 7, in the periphery of which is formed a groove 8, while the opposite or inner end of the hub or spool 6 is formed with an external groove 9 in which rests a reinforcing wire 10, the ends of which are twisted together so as to prevent the splitting of the spool or hub at this end. Supported by the head of the spool or hub 6 are diametrically opposed radial arms each comprising a single strand of wire bent to form an elongated loop 11, the stretches of the wire at the inner end of the loop being twisted together at 12 and terminate in forks 13 having inturned pointed ends 14, the forks 13 being engaged in the groove 8 in the head 7, and the ends 14 are driven into the said head for the mounting of the arms thereon. In this manner the said arms will be securely fastened on the head and the forks 13 by reason of their overlapped relation to each other will reinforce the outer end of the hub or spool 6 to prevent the splitting of this end.

Arranged at the inner end of the spool or hub 6 is a conical-shaped washer or ring 15 which surrounds the bolt 5 and has its bearing against a perforated ear 16 bent at right angles from a shield 17, the bolt 5 being passed through the perforated ear 16 for the mounting of the shield 17 in proper position relative to the spool or hub 6, the shield being formed with an opening 18 through which is passed the operating cord 19 coiled about the spool or hub 6 and which is adapted to operate the brush on the opening of the screen door, as is clearly set forth in my co-pending application filed on or about September 3, 1913, and serially numbered 787,967.

The opening 18 has its edges downwardly and inwardly bent to form a bead 20 which prevents the cutting of the cord 19 when working through the said opening 18 in the shield during the working of the brush.

Trained through the loops 11 of the arms are slotted pieces 21, preferably of oil cloth, and constitute the brushes proper, these pieces 21 being stapled or otherwise secured to the arms as at 22 for the fastening of the same thereon.

The stile 4 serves to support the bolt 5 and is fastened at opposite ends by means of plates 23 through which are passed suitable screw members securing them to the

stile and door frame. This stile 4 also serves to support the weight shield or casing, mounted at the outer side of the door.

From the foregoing it is thought that the construction and manner of operation of the device will be clearly understood, and therefore a more extended explanation has been omitted.

What is claimed is:—

- 10 1. A rotary fly brush comprising a hub having an enlarged head at its outer end, the said head being provided with a peripheral groove, a plurality of arms mounted on the head, each arm being formed from a single strand of wire bent to form an elongated loop and a fork, the stretches of the wire being twisted between the loop and the fork, in-turned pointed ends formed on the fork for engagement in the head to hold the fork seated in the groove therein, and slitted flexible pieces carried by the arms.
- 15 2. A rotary fly brush comprising a hub having an enlarged head at its outer end, the said head being provided with a peripheral groove, a plurality of arms mounted on the head, each arm being formed from a single strand of wire bent to form an elongated loop and a fork, the stretches of the wire being twisted between the loop and the fork, in-turned pointed ends formed on the fork for engagement in the head to hold the fork seated in the groove therein, and slitted flexible pieces carried by the arms.
- 20 3. A rotary fly brush comprising a hub having an enlarged head at its outer end, the said head being provided with a peripheral groove, a plurality of arms mounted on the head, each arm being formed from a single strand of wire bent to form an elongated loop and a fork, the stretches of the wire being twisted between the loop and the fork, in-turned pointed ends formed on the fork for engagement in the head to hold the fork seated in the groove therein, and slitted flexible pieces carried by the arms.

the fork for engagement in the head to hold the fork seated in the groove therein, slitted flexible pieces carried by the arms, and a reinforcing wire trained about the inner end of the hub and having its ends twisted together.

3. A rotary fly brush comprising a hub having an enlarged head at its outer end, the said head being provided with a peripheral groove, a plurality of arms mounted on the head, each arm being formed from a single strand of wire bent to form an elongated loop and a fork, the stretches of the wire being twisted between the loop and the fork, in-turned pointed ends formed on the fork for engagement in the head to hold the fork seated in the groove therein, slitted flexible pieces carried by the arms, and a reinforcing wire trained about the inner end of the hub and having its ends twisted together.

In testimony whereof I affix my signature in presence of two witnesses.

ALLISON F. GODDARD.
